(57) **CLAIM**

The ornamental design for a rolling mechanism, as shown and described.

DESCRIPTION

FIG. 1 is a top perspective view of a rolling mechanism showing our new design;

FIG. 2 is a front elevational view of the rolling mechanism of FIG. 1;

FIG. 3 is a rear elevational view of the rolling mechanism of FIG. 1;

FIG. 4 is a right side view of the rolling mechanism of FIG. 1;

FIG. 5 is a left side view of the rolling mechanism of FIG. 1;

FIG. 6 is a top view of the rolling mechanism of FIG. 1;

FIG. 7 is a bottom view of the rolling mechanism of FIG. 1; and,

FIG. 8 is a top perspective view of the rolling mechanism in condition of use.

The evenly-dashed lines in the figures showing wheels and hardware are to show portions of the rolling mechanism that form no part of the claimed design. The additional elements shown in evenly-dashed broken lines in FIG. 8 are to show environment and form no part of the claimed design.

1 Claim, 6 Drawing Sheets
